CLAIM

The ornamental design for a wireless access point, as shown and described.

DESCRIPTION

FIG. 1 is a top, rear, and left side perspective view of a first embodiment of a wireless access point showing our new design;

FIG. 2 is a rear elevational view thereof;

FIG. 3 is a front elevational view thereof;

FIG. 4 is a left side elevational view thereof, the right side being a mirror image of that shown;

FIG. 5 is a top plan view thereof;

FIG. 6 is a bottom plan view thereof;

FIG. 7 is a top, rear, and left side perspective view of a second embodiment of a wireless access point showing our new design;

FIG. 8 is a rear elevational view thereof;

FIG. 9 is a front elevational view thereof;

FIG. 10 is a left side elevational view thereof, the right side being a mirror image of that shown;

FIG. 11 is a top plan view thereof; and,

FIG. 12 is a bottom plan view thereof.
